UNITED STATES PATENT OFFICE.

JAMES FORREST HOWE, OF WORCESTER, MASSACHUSETTS, ASSIGNOR TO THE AMERICAN STEEL AND WIRE COMPANY OF NEW JERSEY, A CORPORATION OF NEW JERSEY.

MINE-SWEEPING ROPE.

Application filed November 5, 1925. Serial No. 66,975.

This invention relates to wire cables or ropes and more particularly to wire cables or ropes used for mine sweeping or similar operations, and has for one of its objects 5 the provision of an improved cable of this class which will have greater strength and a longer cutting life than cables heretofore provided for the same purpose.

Another object is to provide a cable or 10 rope having the novel construction, design and combination of parts hereinafter described and illustrated in the accompanying drawings:

Figure 1 is a plan of a section of cable 15 constructed in accordance with this invention.

Figure 2 is a transverse sectional elevation.

Referring more particularly to the drawings, the cable is designated as a whole by 20 the letter A, and is composed of alternately arranged cutting and supporting strands 2 and 3 laid up spirally around a core strand 4.

The supporting strands 3 are shown as 25 composed of seven wires 5, and all the wires of each strand are of the same diameter.

It will be understood, however, that I do 30 not wish to be limited to the specific construction of the supporting strands 3, since any well known cable or rope construction may be used for these strands which serve to support the cutting strands 2 and are of a materially less diameter than the strands 2.

The cutting strands 2 are composed of 35 seven wires consisting of a core member 6, which may be composed of wire or hemp, and alternate supporting wires 7 and cutting wires 8. The cutting wires 8 are of materially larger diameter than the core 40 and supporting wires and the core 6 is of materially larger diameter than the supporting wires 7. The alternating supporting and cutting wires 7 and 8, respectively, are laid around the core 6 in a spiral fashion 45 after the well known method of laying up cables, and due to the difference in diameter of the supporting and cutting wires the cutting wires will project beyond the supporting wires so as to present high points 50 to act as cutting elements. The projection of the cutting wires beyond the supporting wires also serves to protect the supporting wires from wear, thereby increasing the life of the strand.

The core strand 4 is preferably of a lesser 55 diameter than the cutting strands 2 and of a greater diameter than the supporting strands 3, and is composed of seven wires 9, all of the same diameter, laid up in the usual manner.

The supporting strands 3 and cutting strands 2 are laid up spirally around the core strand 4 in the usual manner and, due 60 to the supporting strands 3 being of less diameter than the cutting strands 2, the cutting strands will project materially beyond the supporting strands and thus protect them from wear.

It will be understood that I do not wish 65 to be limited to the use of an all wire cable or all wire strands since, if desired, the core strand and core wires or any of them may be composed of hemp or other suitable material.

It will also be understood that I do not 70 wish to be limited to the specific details such as the diameter of the core, number of wires in a strand, particular lay of the wires and strands, and the like, since such details may be changed without departing 75 from the scope of my invention as defined in the appended claims.

I claim:

1. A wire rope for mine sweeping and the like operations, comprising a series of 80 relatively large diameter strands, a series of relatively small diameter strands, and a core strand, said large diameter strands alternating with said small diameter strands and projecting materially beyond said small 85 diameter strands to form cutting elements.

2. A wire rope for mine sweeping and the like operations, comprising a series of 90 relatively large diameter strands, a series of relatively small diameter strands, and a core strand, said large diameter strands alternating with said small diameter strands and being composed of a plurality of alternating 95 large and small diameter wires laid spirally around a core so as to present a series of high cutting surfaces.

3. A wire rope for mine sweeping and the like operations, comprising a series of relatively large diameter strands, a series of relatively small diameter strands, and a core 100 strand, said large diameter strands alternating with said small diameter strands and being composed of a plurality of alternating 105

large and small diameter wires laid spirally around a core so as to present a series of high cutting surfaces, and said large diameter wires being composed of a relatively hard steel suitable for cutting mine cables and the like.

4. A wire rope for mine sweeping and the like operations comprising a plurality of cutting strands alternating with a plurality of supporting strands, said cutting

and supporting strands being alternately arranged around a core strand, said cutting strands projecting outwardly beyond said supporting strands to protect said supporting strands from wear, and said cutting strands having projecting hard steel surfaces for cutting the mine cables or other work. ¹⁵

In testimony whereof, I have hereunto signed my name.

JAMES FORREST HOWE.
